INSULATED CONDUCTOR CONSTRUCTION

Charles W. Abbott, Larchmont, N. Y.

Application October 25, 1941, Serial No. 416,451

42 Claims. (Cl. 174—117)

This invention relates to insulated conductor construction for use in electrical circuits.

One of the objects of this invention is to provide a dependable and efficient insulated electrical conductor construction utilizing, as an insulating medium, synthetic formulations of the synthetic rubber-like classes, in a commercially practical manner and capable of production at reasonable cost. Another object is to provide a conductor construction of the just mentioned character which may be produced in single-conductor or multiple-conductor form and achieve dependable sealing or encasing of the conductor or conductors. Another object is to provide a multiple-conductor construction of the above-mentioned nature in which encasing or insulation of the conductors may be dependably achieved while providing and maintaining sufficient looseness of the conductor or conductors relative to its encasing or insulating covering to insure adequate range of relative movement therebetween as is desirable in certain uses, handling, or installations.

Another object is to provide a practical and inexpensive method of constructing insulated conductors with synthetic materials of the above-mentioned character and which will be readily adaptable or variable according to the practical requirements of the conductor construction and according to various of the characteristics or properties of such synthetic products. Another object is to provide a practical and efficient method of producing insulated conductor construction of the above-mentioned character with the synthetic that is to form the insulation being initially in sheet or strip form. Another object is to provide a practical and dependable method for insulating an electrical conductor or conductors with a thermo-plastic strip or sheet insulating material, that may be readily carried on, on a commercial scale. Another object is to provide a practical and commercially feasible method of applying, in initially strip form, thermo-plastic materials to an electrical conductor or conductors to form the entire or part of the insulation therefor, and to achieve insulation of a conductor or conductors, in the just-stated manner, without detrimental reduction or variation in wall thickness of the applied insulation.

Another object is to provide a practical and reliable method of applying insulated compound in strip or sheet form to one or more electrical conductors, to form the entire or part of the insulation therefor, in a manner to provide and maintain such physical relationship between the

conductor or conductors and the insulation as will permit relative movement therebetween and thus to facilitate installation and handling of the conductor construction, particularly where it embodies more than one conductor, and thus also avoid detrimental compounding of strains either in the conductor or conductors, or in the insulation, or both. Another object is in general to provide an improved and practical method of making insulated conductors.

Another object is to provide simple, practical and dependable apparatus for carrying out the above-mentioned method or methods.

Other objects will be in part obvious or in part pointed out hereinafter;

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawings in which are shown several of the possible embodiments of the mechanical features of my invention,

Figure 1 is a side elevation, partly in vertical section and partly diagrammatic, of one form of apparatus;

Figure 2 is an end elevation as seen along the line 2—2 of Figure 1;

Figure 3 is an end view, partly in section, showing one form of fluting device;

Figure 4 is a plan view as seen along the line 4—4 of Figure 3 of the fluting device;

Figure 5 is a sectional view along the line 5—5 of Figures 3 and 4 showing the action of the fluting device;

Figures 6 and 7 are, respectively, views like that of Figure 1, but showing other and simpler forms of apparatus;

Figure 8 is a fragmentary or partial vertical transverse sectional view as seen along the line 8—8 of Figure 1, indicating a preliminary relationship between conductors and sheet insulating material;

Figures 9 and 9^a are similar transverse vertical sectional views as seen along the line 9—9 of Figures 1, 6, 7 and 25, showing certain preferred structural features of the apparatus and indicating certain possible dimensional relationships therebetween and the materials operated upon;

Figure 10 is a fragmentary detached plan view as seen along the line 10—10 of Figures 1, 6, 7

and 25, showing a form of slitting or parting and sealing arrangement;

Figures 11, 12, 13 and 14 are transverse fragmentary sectional views, on an enlarged scale, of the conductor constructions in certain preferred sequences or stages of carrying out in practice one form of my method and apparatus;

Figure 15 is a transverse fragmentary sectional view, on an enlarged scale, showing how, for example, paired conductors may be constructed;

Figure 16 is a view like that of Figure 9 illustrating a different conformation of certain of the elements;

Figures 17 and 18 are transverse fragmentary sectional views, like Figures 11 and 12, of the conductor constructions, illustrating certain steps and features of construction resulting therefrom;

Figure 19 is a view like that of Figure 9 showing a modified configuration of certain of the parts of the apparatus;

Figure 20 is a transverse fragmentary sectional view on a large scale showing the conductor structure resulting from the apparatus of Figure 19;

Figure 21 is a view like that of Figure 20 showing a modified form of conductor structure and apparatus;

Figure 22 is a transverse sectional view on a large scale showing a conductor structure resulting from carrying further certain aspects of my method;

Figure 23 is a plan view showing diagrammatically certain of the steps for producing the structure of Figure 22;

Figure 24 is a transverse sectional view on a larger scale as seen along the line 24—24 of Figure 23;

Figure 25 is a view like Figure 1 illustrating another mode of carrying on my method and showing an illustrative apparatus for so doing;

Figure 26 is a view like that of Figure 12 showing, in fragmentary transverse section on an enlarged scale, a conformation of certain of the elements for effecting or facilitating parting;

Figure 27 is a transverse sectional view as seen along the 27—27 of Figure 26; and

Figure 28 is a fragmentary plan view showing the insulated multiple conductor structure resulting from the steps and apparatus of Figures 26 and 27.

Similar reference characters refer to similar parts throughout the several views of the drawings.

It has heretofore been proposed to insulate one or more electrical conductors by rolling or pressing, longitudinally thereof and from two semi-circular sides thereof, two strips of natural rubber with the inner faces thereof bearing a cement or with one or both of them of unvulcanized rubber, or by rolling or pressing two sheet materials like fabric, paper or the like, bearing an adhesive or other cement on their inner faces, whereby the strip material is compressed tightly all around the conductor or conductors and becomes bonded together and to the conductors, either by the cement, adhesive, vulcanization or otherwise, but I am unaware that any such proposals have proven practicable or commercially successful, excepting for so-called "strip insulation" where two strips of vulcanizable rubber are rolled or pressed around and against the two sides of conductors and thereafter vulcanized by methods which are slow, cumbersome and expensive, limiting the resultant

construction to a considerable degree. Additionally, the insulated conductor or conductors that result from carrying out such proposals are deficient for numerous reasons, rendering them impracticable for numerous important uses and installations, and among them may be mentioned the difficulty or impossibility, particularly with natural rubber, of achieving, by the proposed methods, consistent uniformity of wall thickness; the costliness of carrying out commercially certain of these proposals; the virtual impracticability of commercially practicing such proposals with the use of natural rubber utilizing cements; the expense and additional cumbersome processing where vulcanization is used to secure bonds; and also the fact that the bonding of the insulating covering to the conductor or the tight enclosure by the covering of the conductor prevents freedom of movement therebetween during bending or the like, with the result that strains are set up in the conductor or the insulation or both, which strains when compounded by multiple bending may result in insulation rupture or breaking of conductor strands. One of the dominant aims of this invention is to provide a practical and economical insulated conductor construction utilizing sheet or strip materials in a manner and by methods which will avoid the deficiencies and disadvantages of such prior constructions and have other useful superiorities thereover, and to provide a practicable method and apparatus for making possible the utilization of certain insulating materials, heretofore considered impossible of such use, in sheet or strip form, in the quantity production of insulated conductor.

Furthermore, and as is well known, ordinary rubber compounds as used for insulating wire have a number of inherent characteristics which are disadvantageous when used for the insulation of conductors; thus, for example, rubber is detrimentally affected by various oils and by petroleum products, it oxidizes, it deteriorates under the action of sunlight and it burns freely, and hence, either corresponding precautions have to be taken in the use or application of rubber-insulated conductor or special provisions have to be made structurally to effect protection of the rubber itself. For example, in electrical wiring construction such as the type that utilizes boxes, such as outlet, junction and distribution boxes, wherein considerable numbers of rubber insulated conductors are present, the conductor employed has over its rubber insulation a covering, usually made of asbestos or fabric serving or braid, so saturated and treated as to be resistant to fire which may originate in such boxes from various causes. There are, however, a number of materials lacking such deficiencies as those just mentioned in connection with rubber and which, moreover, are superior to rubber in other respects in that, for example, they are tougher and stronger, do not damage as easily as rubber, are more resistant to blows, abrasions, tearing strains and the like, and can be employed in lesser thicknesses for insulation purposes than rubber, and yet have not been found thus far capable of general use in the insulation of conductors upon a basis commercially practicable or upon a reasonable cost basis, or both, excepting in special and usually costly constructions.

Among such materials are the so-called synthetic rubbers, and like or analogous synthetic formulations and of these there are certain particularly desirable materials that are recognized

as being non-vulcanizable and which, while pliant and having broadly other physical properties of natural rubber, are thermo-plastic, and it is these which I have discovered may be processed, according to my method, in conjunction with a conductor or conductors to produce, on a basis of reasonable cost and commercial feasibility, insulated conductors capable of wide uses and applications far beyond those of the few costly and special insulated conductors thus far produced with the aid of synthetic products.

Among the unvulcanizable synthetic materials having thermo-plastic characteristics suitable for processing according to my invention, I prefer to employ, and set forth as examples or illustrations, plasticized vinyl chloride polymers, such as those known and available on the market as "Koroseal" and "Flamenol" and "Korogel," polyvinyl acetate, such as is known under the tradename "Formvar" and polyvinyl chloride-acetate, such as is known under the tradename as "Vinilite," and isobutene polymers, such as is known under the tradename "Vistanex." These materials, moreover, can be produced in sheet or strip form of substantial lengths, as in rolls, and in suitable thicknesses, preferably thicknesses on the order of 0.010" or 0.050", according, of course, to the insulating and other properties which are desired in the insulated conductor construction, and hereinafter I refer to these materials, or their comparable equivalents, as "sheet material" or "strip material."

How I process, with a conductor or conductors, materials such as those just mentioned and which are non-vulcanizable and have thermo-plastic characteristics, will be better understood and grasped if consideration is first given to a possible form of apparatus, that of Figure 1, for example, that may be employed in carrying out one form of my method, and in this form of apparatus, the latter may comprise a suitable frame having suitable side frames or standards 20 and 21 provided with suitable means, such as detachably mounted spindles 22, 23, for supporting rolls 24 and 25, respectively, of the strip or sheet material to be employed. The latter may be of any suitable width, as viewed in Figure 2, usually depending upon the number of conductors and their diameter which are to be simultaneously covered, and in length, the material may be of any suitable dimension.

The web or sheet material of the rolls 24 and 25 I arrange to draw off of the latter and into juxtaposition to each other, but with the conductors to be covered drawn along with the ends of the webs, in between the latter, and at the same speed, and that three-element entity I then bring into the zone of action of two co-acting heater and presser elements, preferably taking the form of rollers or drums 26 and 27, (Figures 1, 2, 6 and 7) and certain preferred features of construction and action of which are later described, though it may, at this point, be noted that the drums 26-27 are heated in any suitable way as illustratively later described.

Depending upon various factors, such as the particular thermo-plastic characteristic of the sheet or web material, its thickness, the diameter of the conductor or conductors to be covered, the rate or speed of action of the elements 26 and 27 upon the web material relative to the conductors, I may find it desirable, in effect, to partially preform the web material or somewhat preheat it, or both, and where both such steps 75

are desirable, I may utilize a form of apparatus like that shown in Figure 1.

Thus, I may arrange drum 27 above drum 26 and, in such case, I prefer to mount the web roll 25 at an upper portion of the frame and web roll 24 at a lower portion of the frame (see also Figure 2), and guide the sheet or web material into proximity to the heated drums so as to become warmed thereby, to substantially the desired extent. Thus the sheet or strip material 28 from the roll 24 may be passed about guide rollers 30, in suitable number, and which are preferably arranged substantially along an arc whose center may be at the axis of drum 26 and whose radius is sufficiently greater than the maximum radius of drum 26 so as to guide the moving web 28 at the desired distance from the heated drum and about a substantial arcuate extent thereof to become warmed by heat emanating from the drum, thus to give the web material better pliancy for the subsequent steps. In similar manner, web 29 from the roll 25 may be guided over similarly positioned guide rollers 31, but spaced about a substantial arcuate extent of the upper drum 27, thus to improve the pliancy of the material for the subsequent step. Where such an arrangement is utilized, waste of heat from the two operating drums is diminished.

For preshaping the moving web material, thus initially warmed, where that step is desirable, I provide suitable means for, in effect, longitudinally fluting the two webs and a preferred form of apparatus for so doing comprises a lower device, generally indicated by the reference character 34, for operation upon the lower web 28 and an upper device 35 for operating upon the upper web 29. These devices are preferably of identical construction and hence only one need be described in detail, though in relation to the operating throat formed between the drums 26-27, the one device is inverted relative to the other. Each has an entry end for the web material, at its right hand end as seen in Figure 1, into which the web enters in flat or plane condition, and an exit end at its left hand end and adjacent the operating portions of the drums 26-27, the webs emerging from the left hand ends longitudinally corrugated or fluted and with the transversely spaced conductors therebetween, in the general relationship indicated in Figure 8, where the conductors are shown at 36.

The two devices 34 and 35 each comprise two sets of companion fluting elements 40 and 41 (Figures 3, 4 and 5) which, in the illustrative form, may be made of relatively stiff, but somewhat springy, wire of a diameter commensurate with the diameter of the conductors 36 and, in such case, may be given a shape and mounting as shown in Figure 4.

Thus the upper set of fluting elements 40 are mounted in any suitable way to be parallel to each other, as for example, by securing them to a rod 42 mounted in any suitable way in the side frames 20, 21, preferably adjustably in a direction toward or away from the companion fluting elements 41 and preferably also about the axis of rod 42, as indicated by the arrows in Figure 3; from the rod 42 each fluting element has a substantially elongated and slightly curved portion 40^a terminating in a bent-over front or leading portion 40^b, and the spacing of the elements 40 crosswise of the web and hence lengthwise of the supporting rod is preferably equal and on the order of the spacing desired between the several conductors.

In a similar manner, though inverted, as better appears in Figure 3, fluting elements 41 are mounted on a supporting rod 43, adjustable toward or away from the rod 42 and preferably also about its axis, as indicated by the arrows, each element 41 having an elongated, somewhat curved, portion 41^a and a curved over or leading portion 41^b. Elements 41^a are also parallel to each other, spaced according to the spacing desired between the several conductors, but the assemblage of the two parts of the fluting device 42-40 and 43-41 or the mounting of the fluting elements on their respective supporting rods is such that elements 40 alternate with elements 41 and each extends centrally between two adjacent elements of the other, as is better shown in Figure 4. The setting or adjustment, as by setting or adjusting either or both of members 42 and 43 is somewhat as indicated in Figure 3, so that as the web is drawn in between the two sets of fluting elements 40 and 41, the web becomes interrelated thereto, as is better shown in Figure 5, becoming longitudinally fluted or corrugated as it moves along.

The leading curved ends 40^b and 41^b insure smoothness of initial action of the fluting elements upon the moving web material and the portions 40^a and 41^a thereof may be initially bent or curved to effect a progressively deeper or greater fluting action as the material progresses from the leading ends thereof toward the rear ends.

Preferably, also, the fluting elements are arranged to have effective fluting portions positioned, at least at their forward or leading ends, in the shape of a V, with the apex aligned with the center line of the moving web material and pointing in the direction from which the material feeds, as for example, toward the guide roller to the right of the fluting device, as seen in Figure 1.

Such an arrangement assures that the flutings in the moving strip or web material are successively formed from its center line outwardly in both directions, thereby avoiding harmful straining or stretching or distortion of the web material, the overall width of which, when it emerges from the fluting device, being, of course, less than its initial width. Also, and depending upon various factors, where partial preheating is employed, the fluting action is facilitated or eased by the increased pliancy of the web material resulting from preheating. The depth of the flutes or corrugations and also the rate of progressive fluting action of the fluting elements to either side of each web may be determined by adjustment of the two sets of fluting elements (see Figure 3), toward or away from each other or by varying the settings thereof about the axes of the mounting rods 42 and 43, or both.

The two fluting devices 34-35 are related to each other in the general manner shown in Figure 1, that is, with the one inverted relative to the other, and it is through the space between the two devices 34-35 that the conductors 36 are moved or drawn in a direction toward the left as viewed in Figure 1, and for greater convenience of access and of arrangement, the devices 34-35 and hence their parts may be given an inclination relative to the plane along which the plurality of conductors 36 are moved toward the left, the plane of movement of the parallel spaced conductors 36, in effect, bisecting the angle formed by the two devices, with the conductors emerging at the apex of that angle.

The conductors 36, which may be solid or stranded wire, are supplied from respective reels diagrammatically indicated at 51 and, respectively, provided with suitable braking means or the like to give each conductor 36 the desired tautness or tension. Preferably also, suitable means such as a guide comb, diagrammatically indicated at 52, are provided to fix the spacing between whatever number of conductors 36 are to be treated, and here the spacing is related to the fluting effected by the fluting devices 34 and 35, or vice versa, and the fluting effected by device 34 is the reverse of the fluting effected by the device 35, the relationships being better shown in Figure 8 from which it will be seen that, as the conductors 36 emerge from or pass through the apex of the angle between the two fluting devices of the fluting assembly 34-35 with the now fluted web 29 above them and the now fluted web 28 below them, the interiorly concave portions of the two webs 28-29 face each other and each pair of such juxtaposed concave portions of the two webs has therebetween a single conductor 36.

Suitable means may be employed to vary the warming effect upon the sheet material by the drums as, for example, by changing the spacing of the rollers 31 and 30, respectively, from the drums 27 and 26, and for this purpose, these rollers may be mounted adjustably by any suitable means not shown, but indicated by the arrows in Figure 1.

Where various factors, such as those indicated earlier above, do not require fluting or pre-shaping of the sheet material, the fluting devices 34 and 35 may be omitted, whence the arrangement shown in Figure 6 may be employed where it is still desired to warm up the sheet material, as by letting it obtain heat from the respective drums. Also, there can be present factors which do not require either fluting or pre-warming and, in such case, I may eliminate these two steps and the corresponding fluting and heating means, leaving the apparatus in substantially the form indicated in Figure 7, where the position of the supply rolls 24 and 25 may be shifted rearwardly or to the right of the apparatus and their respective webs 28 and 29 guided along paths not thermally related to the drums, as by suitable guide rolls 60 and 61, respectively, and to bring them into operative relation to the parallel conductors 36, with web 29 brought above the conductors and web 28 below the conductors, thus to enter the three-fold entity comprising the two webs with the parallel spaced conductors between them, into operative relation to the drums 26 and 27.

The drums 26, 27 are driven by any suitable means so that their adjacent portions move in the same direction, in the direction toward the left in Figures 1, 6 and 7, and preferably at the same surface speeds, and preferably at a surface speed the same as the speed or rate of linear movement of the conductors 36 which, with one sheet material 29 overlying them and the other sheet material 28 underlying them, are to have their assemblage completed by the action thereon of the drums 26, 27. For thus driving the drums, any suitable means may be employed, such as a shaft 63 (Figure 2) driven from any suitable source of power, not shown, and geared as by pinion 64 to a gear 65 on the shaft of drum 26 and, in turn, being in driving connection, as by suitable gearing 66 with the shaft of drum 27, the gearing being arranged so that, as viewed in Figures 1, 6 and 7, drum 27 is driven in clock-

wise direction and drum 26 in counterclockwise direction.

The rate of movement of the conductor or conductors 36 toward the left may be determined and the movement effected by any suitable means, such as for example, by a capstan sheave or sheaves 69 driven in any suitable way, as by shaft 70, preferably at the same surface speed as the surface speed of the drums 26-27, and hence may be synchronized with the drive of the drums in any suitable way, not shown. The capstan sheaves 69 are preferably aligned with the guiding means 52, Figures 1, 6 and 7, so that, at the desired tautness, as may be determined by the braking means associated with the reels 51, the plurality of conductors 36 lie in the same plane which passes intermediate of the two drums 26-27, are given the desired spacing, preferably equal spacings, one from each other, as indicated in Figure 8, for example, and, where the partial preshaping or fluting is employed, the flutings in each web, as above explained and as will now be clear, are spaced center line to center line according to the spacing between the conductors 36, as indicated in Figure 8.

The drums 26, 27 of Figures 1, 6 and 7 are constructed to act upon the thermo-plastic material of the sheets or webs 28, 29, to effect certain actions which will be clear after consideration of a preferred form of construction of the drums 26, 27.

Thus, I arrange to maintain the operative portions of the drums at a temperature suited to the particular thermo-plastic characteristic of the sheet material employed, as is later set forth in greater detail and a preferred arrangement for supplying heat to the drums 26, 27, comprises constructing the drums to be hollow and supplying the interior space thereof with a suitable heating medium, such as steam, or a heated liquid like oil.

Thus, for example, as indicated in broken lines in Figure 2, the hollow space 26^a within drum 26 may be supplied with heating medium through a hollow shaft or trunnion 73 through which, and preferably coaxially therewith, extends a smaller-diametered pipe or conduit 74, the one serving as an inlet passage and the other for an outlet passage, so that the heating medium may be continuously passed through the drum to keep its cylindrical shell and the operative portions thereof at the desired temperature.

In a similar way, the interior 27^a of drum 27 may have a hollow shaft or trunnion 76 through which extends a smaller-diametered pipe 77. The hollow trunnions and the tubes or pipes that extend through them are connected into the circulating system of the heating medium by any suitable means, such as conduits or piping 79 connected to the outer ends of the pipes 74 and 77 as by suitable stuffing box or gland connections 80, with suitable valve controls 81, while the hollow shafts 73 and 76 are connected by piping or tubing 83 through suitable stuffing box or gland connections 84, preferably including also valve controls 85. In detailed construction, these connections may be given any suitable known form. Thus, during rotation of the drums, they may be continuously supplied with a fluid heating medium and any suitable means, illustratively the valves 81 and 85, may be used and thermostatically controlled to govern the rate of flow and temperature input of the heating medium and thus suit the rate at which heat is supplied to the operative portions of the drums to the

functions which they are to perform upon the thermo-responsive material of the webs and according also as the latter may, or may not, be pre-warmed or pre-shaped.

- 5 The operative portions of the drums 26, 27 are preferably constructed substantially as indicated in Figure 9 to present a succession of companion annular elements 26^b and 27^b spaced from each other axially and in relation to the spacing from each other of the conductors 36, presenting to each other substantially cylindrical operative faces 26^c and 27^c, respectively, though it will be understood that these faces may be varied somewhat in configuration, being, for example, rounded off or chamfered somewhat to avoid presenting sharp corners or edges.
- 10 The operative annular elements 26^b, 27^b, are preferably of radial dimensions greater than the maximum vertical radius, as seen in Figure 9, of the assembled conductors and sheet material, or may be otherwise shaped or constructed, as by providing annular spaces 26^e, 27^e, respectively, between them and of a depth or cross-sectional shape or dimensions preferably to avoid substantial pressing or engagement of the side or bottom walls of the annular spaces against or with the sheet material below and above the conductors, as viewed in Figure 9, as will become clearer later hereinafter.
- 15 In axial dimension, the faces 26^c, 27^c of the annular elements 26^b, 27^b, respectively, are preferably equal to a factor which is the dimension of the actual space between two adjacent conductors less twice the thickness of the sheet material of the webs 28, 29. The drums 26, 27 are preferably mounted in the frame elements 20, 21 (Figure 2) to be vertically adjustable, preferably toward or away from one another, in any suitable manner, as by the hand-wheels and screws 20^a and 21^a (Figure 2) operating upon the slidably mounted bearing blocks carrying the drums and as indicated by the arrows in Figures 1, 6 and 7, it being understood that the drive of the two drums and the connections thereof to the circulating system are constructed in any suitable way to allow for such adjustment. The drums are set so that the spacing, as viewed in Figures 2 and 9, between companion operative faces 26^c and 27^c is less than the sum of the thicknesses of the two sheet materials 28, 29, and by way of illustration, it being noted that the sheet materials 28, 29, are preferably of equal thicknesses, this spacing may be on the order of one-half of the sum of the two thicknesses. Thereby I insure that, as the three-fold entity of conductors 36 with the sheets or webs 28, 29 pass in between the drums, the portions of the two sheets intermediate of the successive spaced conductors are subjected to pressure, and in the preferred arrangement, the annular operative elements 26^b and 27^b, being heated to the desired temperature, communicate heat only to these intermediate portions of the two sheet materials, while under pressure.
- 20 As will be seen upon viewing Figures 1, 6 and 7, the throat formed by the operative elements of the drums 26, 27 converges or gradually narrows itself, so that the action of the companion pairs of heater and presser elements 26^b, 27^b is in effect a gradually progressive action, and where these elements are constructed in rotary form, as in the preferred embodiment, their movement inwardly toward the narrowing or narrowest portions of the throat effects a progressive action, which, among other things, effects fluting of the

- 75

two webs or sheets about the respective upper and lower half-cylindrical surfaces of the conductors where preliminary fluting is not utilized as in Figures 6 and 7, or completes the proper fluting or laying of the sheet materials against the two longitudinal upper and lower half surfaces of the conductors, where the preliminary fluting or so-called pre-shaping, as in Figures 1 and 8, is utilized.

Thus, in Figure 11, I have indicated somewhat schematically an earlier stage of the action of the presser and heater elements, such as the action that takes place at that portion of the converging throat where the companion elements 26^b and 27^b have a spacing of about the sum of the thicknesses of the two sheet or web materials 28, 29, so that the portions 28^a and 29^a thereof that are intermediate of any two successive conductors 36 have their adjacent faces brought just about into engagement with each other. It will be understood that, because of the preferred shaping of the throat and, particularly, where pre-fluting is not resorted to, these intermediate portions may be engaged by the heated presser elements, earlier than the stage indicated in Figure 11, depending upon the angles at which the webs 28, 29 are fed to the throat relative to the line or plane of the conductors 36, thus receiving heat therefrom at an earlier stage. The heat flows into the portions 28^a, 29^a, and as the three-part entity of sheet materials 28, 29 with interposed conductors 36 continues to move to the left, as viewed in Figures 1, 6 and 7, and beyond the stage indicated in Figure 11, the throat continues to narrow up, and the now heated portions 28^a, 29^a become compressed and pressed against each other, to a greater and greater extent until the narrowest portion of the throat is reached, by which time maximum heat and pressure effect by the elements 26^b and 27^b upon the portions 28^a and 29^a, respectively, has been accomplished.

Where the minimum spacing between the presser and heater elements is, in dimension, one-half of the sum of the equal thicknesses of the sheet materials 28, 29, the above-mentioned final stage of heating and compression finds the structure somewhat in the relationship shown in Figure 12, where it will be seen that the portions 28^a and 29^a have been reduced in thickness and, in the assumed illustration, have been reduced to one-half their original thickness.

Accompanying these physical actions, the heat transfer to the portions 28^a and 29^a has been of such magnitude that the material, due to its thermo-plastic characteristics, has throughout the regions of the portions 28^a, 29^a become soft and in effect plastic, and under the pressure effect, plus its condition of mobility due to its temperature, the materials of the two portions 28^a and 29^a practically flow or merge together to effect a bond or union. The heating of the portions to be bonded is preferably to a temperature just below or approximating the melting point of the particular material employed in the sheets or strips 28, 29.

The now bonded portions 28^a, 29^a emerge to the left, as viewed in Figures 1, 6 and 7, from the narrowest portion of the throat and hence come out of heat transferring contact with the heating and pressing elements, the latter, being cylindrical and rotary in the preferred form, and providing to the left an exit throat which is divergent, thus to permit the moving conductor assemblage to come out of direct contact with the

heater and presser elements, whence cooling off commences. Further cooling off is also effected by the absorption of heat by the metal of the conductors themselves which, when made of copper, as is usually the case, have a high heat capacity, or the cooling may be accelerated as later described.

In these actions, I make it possible to avoid stretching of the arcuate portions 28^b and 29^b of the sheets 28 and 29, or if stretching does take place, it is of inconsequential magnitude or effect. Thus the progressive compression of the intermediate longitudinal regions 28^a, 29^a in passing from the stage of Figure 11 to the stage of Figure 12 is accompanied by the substantial heating action and causes the material, being now substantially plastic or mobile, to move to the right and left, as viewed in Figure 12, and hence so much of it as cannot be accommodated in the progressively narrowing and in the finally narrowest space between the faces 28^c, 27^c of the elements 26^b and 27^b, respectively, is forced out from in between these faces and, in effect, adds itself equally to the arcuate portions of the sheets, thus counteracting tendency to stretch or tensioning in these arcuate portions 28^b, 29^b or, in effect, relieving any material tension that might be present therein. This mobility of the material to extend itself in directions to become part of the arcuate covering portions practically ceases upon emergence of the assemblage from the narrowest portion of the throat, whence cooling off takes place.

Thus, companion portions of the two sheets become laid against the two respective convex halves of the conductors, but without adhesion or bonding to the latter and with a looseness of fit, as indicated at x, that gives adequate leeway for possible shrinkage of the material of the casing of each conductor while retaining the capacity for relative ease of relative movement between the conductor and its immediate casing, particularly upon bending or curving. Though the material of the portions 28^a, 29^a is, during the process, practically plastic under the heat effect, I have found that those portions that have some mobility or are plastic or flowable under pressure and which might be in engagement with small regions of the conductors adjacent the junction formed between the portions 28^a, 29^a, do not adhere to the conductors, apparently because a sufficiently high degree of plasticity does not exist where direct contact of the material with the conductors might take place or perhaps because the metal of the conductors removes the heat from any otherwise sufficiently plastic material in contact with the metal as to reduce its mobility or plasticity to a degree below that causing adhesion.

The temperature to which the strip materials are heated are, as above pointed out, preferably below the melting point of the particular material employed. For example, where the melting point of certain formulations of "Koroseal" is 160° C., the heating of the portions 28^a and 29^a by the heater and presser elements is on the order of 150° C. It will, of course, be understood that this temperature may be varied to suit the particular circumstances; for example, at slower speeds of movement through the heater and presser elements, a slightly lower temperature of heating might be employed. Also other factors, such as the amount or character of plasticizer employed may affect the temperature to which the heater and presser elements are made effec-

tive upon the material. But with an apparatus like that above described, and for any desired or selected composition or formulation of the material of the sheets or strips employed such as, for example, "Vistanex," "Vinilite," "Formvar," etc., the temperature of heating may be comparatively quickly determined empirically. For example, certain synthetic formulations have a tendency to, or characteristics of, disintegrating or "sugaring" when heated to a certain degree, and, in such case, care should be taken to determine the temperature at which the sealing together or bonding is to take place at a value below the disintegrating temperature. Others, like "Koroseal," I have found exhibit a range of temperature within which the bonding or sealing action may be effected, other conditions such as thickness of the material, speed of movement thereof, etc., being correspondingly suited to any selected temperature within such range; thus, with "Koroseal" of a formulation containing about 40% of plasticizer and having a melting point of approximately 160° C., I have found that it bonds together fairly well at 141° C., makes a satisfactory bond at 147° C., and practically welds or melts together at approximately 150° C., operating upon strips or sheets having a thickness of 0.015". Others have relatively fixed heating points or narrower ranges; for example, with "Formvar" the bonding temperature is substantially critical, being, I have found, just about 100° C.

I am thus enabled, according to the thermoplastic characteristics of the material employed, and without having to have recourse to slow, cumbersome and costly vulcanization of the vulcanizable rubbers, either synthetic or natural, to achieve dependable encasing of the conductor or conductors, and, according to circumstances, the junction effected between all of the pairs of longitudinally extending portions 28^a and 29^a, as in Figure 12, may vary somewhat in character; thus the junction may be effected, under the heating and pressure effect, by what is in the nature of a bond brought about by tackiness or adhesiveness during the heating and pressing, or it may be in the nature of an actual flowing together or fusion of the heated mobile masses of material in the portions 28^a, 29^a, depending upon such factors as the heat and pressure employed and the nature of the particular material employed. In the former case, there may be present in the final structure as it emerges from the stage shown in Figure 12 and after it has been cooled, a perceptible plane, suggestive of a plane of cleavage, between the bonded-together parts 28^a, 29^a, and in the latter case such a plane is hardly, if at all, perceptible or present.

Preferably, I provide means for more effectively and quickly cooling off the multiple insulated conductor structure, upon its emergence from in between the heater and presser elements and hence upon its emergence from the stage indicated in Figure 12. Thus, for example, I may provide for blowing air onto the upper and lower sides of the multiple conductor structure and into the respective angles which it forms with the drums 26 and 27, as by suitable air guiding means or jets 88 and 89 as indicated in Figures 1, 6 and 7, or I may run the structure through a liquid cooling bath diagrammatically indicated at 91, or both, thus restoring the heated portions of the webs, now assembled together and to the conductors, as above described, to their initial or room temperature and thus restoring the in-

ital characteristics of the material that was heated, such as its pliancy, strength, toughness, capacity of stretch, and the like, whence, if desired, the multiple insulated conductor structure 5 may be put into use, or if desired and according to certain other aspects of my invention, may be further processed as is later hereinafter described.

As a multiple insulated conductor structure, 10 it may comprise any number of conductors, of which only two are shown in Figure 12 and, illustratively, but not by way of limitation, 200 conductors 36 may in such a single operation be so enveloped or encased between two web or 15 sheet materials which, if the process is carried on even at as slow a rate of movement relative to the heater and presser elements as 25 feet per minute, results in a production of linear footage of 5,000 feet of insulated individual conductor per 20 minute.

The resultant band-like form of structure or 25 desirable longitudinal sections thereof, may be employed as such, is characterized by great ease of pliancy, longitudinally, and hence readily adaptable to attachment flat-wise to surfaces, being capable of repeated bending into and about corners, curves, angles and the like. In this latter connection, the relative ease or freedom of relative movement between each conductor and 30 its individual casing makes such application to repeated bending or curving when applied to broken or irregular surfaces, possible, in that conductor and casing are, independently of each other, accommodated to the bend or bends and 35 hence setting up and multiple compounding of harmful strains in the conductor or casing, particularly where the conductor is stranded, do not take place due to this ease of relative movement.

This ease of relative movement and freedom 40 from adhesion between the conductors and their enclosing insulation also makes possible the ready "stripping" or "baring" of the individual conductor or conductors at the end or ends of a run or length of the insulated conductor structure. This 45 may be quickly accomplished by stretching, as by pulling, the multiple casing structure beyond the already cut-off ends of the conductor and cutting it off, whence the recovery of the material due to its elasticity causes the cut-off end 50 of the casing to recede from the ends of the conductor or conductors, thus baring the latter; or, before cutting the multiple conductor structure, the casing part thereof may be stretched relative to the conductors, and when both the conductors and the stretched casing are then 55 cut, the recovery of the casing causes its cut end to recede from the cut end of the conductor or conductors, thus baring the latter.

There is also present wide flexibility transversely of the band-like structure, flexing taking place in the regions of the joined-together longitudinal portions 28^a and 29^a, as seen in Figure 12, and the structure may be folded or rolled up about these joined-together portions as axes of transverse bending. Along these portions also, the structure may be slit or cut, to divide it, or only portions of its length, into two or more branches, each of one or more insulated conductors and the branches may be cut off at such lengths as may be desired, the stretchability and recovery of the casing material in conjunction with the above-mentioned ease of relative movement between the casing and the conductors greatly facilitating the stripping or 75 baring at the ends.

Moreover, great compactness can be achieved. For example, and in dimensions, using #16 stranded conductor, having a diameter of 0.055", and a sheet material of 0.015", it will be seen that the thickness of the band-like multiple insulated conductor is increased by only 0.030" and the actual spacing between adjacent conductors may be on the order of 0.060", where the heater and presser elements 26^b and 27^b of Figures 11 and 12 are given a transverse dimension or thickness of twice the wall thickness of the sheet material itself.

I make provision also, as above indicated, for continuously separating encased conductors into single conductor, two conductor or other multiple conductor units to thus provide insulated conductor or conductors for general wiring applications or to form lamp cords, circuit extension materials, etc., or to form the basis for a built-up insulated conductor structure such as armored cable, so-called non-metallic sheathed cable, and the like.

Here I prefer to provide, referring now to Figures 1, 6, 7 and 10, a heated parting or severing element, one for each line of severance to be effected and, in the above assumed illustration, one for each of the longitudinally extending joined-together portions 28^a, 29^a (Figure 12) of the structure, spacing them correspondingly transversely of the plane of movement of the conductor structure toward the left, and, as better appears in Figure 10, and because of the relatively small spacings, these heated parting elements, each generally indicated by the reference character 92, may be staggered. Each may comprise (Figures 1, 6 and 7), a blade-like member 93 and a heater element 94 therefor, the latter being preferably any suitable form of electrical heating unit provided with any suitable means, such as a rheostat, for controlling or setting its heating action, or effect.

Each heater parting element 93 is maintained at a temperature that is preferably at, or somewhat above, the melting point of the particular formulation of the sheet material employed. Thus, in the case of "Koroseal," a temperature of 160°, if that is the melting point, or preferably slightly above, is made effective, and as the composite or multiple structure is drawn along, as by the capstan sheaves 69 operating upon the separated insulated conductors, with the heater and parting elements 93 positioned to operate in a vertical plane, that is, the central plane of the joined-together portions 28^a and 29^a, the material of these two portions to each side of the heater and the parting element 93, in each case, is raised to a temperature on the order of the melting point of the material of the sheet employed, or slightly above it, thus greatly easing and facilitating the parting action and, at the same time, causing a fusion or flowing together of the respective halves of the portions 28^a and 29^a thereby completely or sufficiently eliminating any plane of cleavage therebetween and resulting in longitudinal junctions of the arcuate covering portions 28^b and 29^b, somewhat as indicated in Figure 13, as at 96.

While still heated and in somewhat mobile state, the external surfaces of the junctions 96 may be smoothed down, crimped or ironed out by any suitable means, such as presser or roller elements 97 (Figure 10) and when any such longitudinal protrusions are thus or otherwise removed or ironed out, the resultant casing for the individual conductors 36 appears somewhat

as indicated in Figure 14. Immediately thereafter, I prefer to withdraw the heat from the heated junction portions and here I may employ a cooling liquid bath, as indicated diagrammatically at 98, in Figures 1, 6 and 7, whence the now individual insulated conductor structures pass, respectively, over their capstan sheaves 69 and onto their respective reels 99.

Should it be desired to produce insulated 10 conductors, such as for lamp cord, for example, the heater and parting elements 92 are positioned so as to operate upon every alternate joined-together portions 28^a and 29^a, whence the former band-like multiple conductor structure 15 emerges from the heated parting elements in pairs of conductors, joined together as indicated in Figure 15 where two such pairs are shown, and thereafter chilling of the junctions 96 may be proceeded with, with or without smoothing 20 off, or ironing out, of any longitudinal protrusions representing the junctions 96.

It might at this point be noted that, where the 25 particular formulation or composition employed in the strips or sheets, has a tendency to shrink when elevated to high temperatures, the cooling or chilling actions above mentioned work in opposition to such shrinking action and this opposition or counter-effect, effected by withdrawing heat from the sheet material, may be materially aided by the rapid withdrawal of heat by the metal of the conductors which enter the apparatus in unheated condition or which may, if desired, even be pre-cooled by any suitable heat exchange means, indicated diagrammatically, in 30 Figures 1, 6 and 7, at 101; the means or device 101 may take any suitable form such as a cold air blast, or the like, through which the conductors 36 are passed or into thermal-relation to which they are brought in any suitable way. The 35 absorption of heat by the metal of the conductors, during the relatively short time interval that the strip or sheet materials are undergoing heating by the heater and presser elements, thus protects the walls formed by the sheet material about the conductor from being raised to a high enough temperature, to let any shrinking effect become of material consequence, insofar as maintaining relative ease of relative movement between the individual conductor and its casing is concerned.

In giving the heater and presser elements 40 shapes or conformations like those described above in connection with Figure 9, in that the heated presser elements preferably do not come into contact with the arcuate or semi-circular portions of the sheet material, like the portions 28^b, 29^b, of Figures 11 and 12, direct heat transmission to these portions is avoided, and thus raising of the temperature of these portions in 45 that manner cannot take place and the shrinking tendency, if present in the particular material employed, is thus also not encouraged.

The method and apparatus readily lend themselves to meet particular situations or requirements. Thus, for example, where it is desired to produce the multiple insulated conductor structure, in band-like form, without slitting or severing, leaving the parting of one or more insulated conductors from each other or from the rest, to be done in the field, as by a knife or scissors, it may be desirable to have the joined-together portions 28^a, 29^a of Figure 12 of greater width, and in such case, the heater and presser elements are constructed to have their operative faces 26^c and 27^c of Figure 9 of greater width

as viewed in that figure, the spacings center to center of the conductors 36 being correspondingly or appropriately increased.

However, I prefer to provide for greater ease of parting or separation, as by cutting with scissors or a knife by effecting, at the center of the junction represented by the portions 28^a, 29^a of Figure 12, a region or zone in which the bonding or flowing together is, either entirely absent, or is weaker mechanically than to either side of that zone. This I may effect by shaping the heater and presser elements 26^b and 27^b of the drums 26 and 27, as shown in Figure 16, which otherwise corresponds to Figure 9, and as shown in larger scale in Figure 17, which otherwise corresponds to Figure 12, where the operative faces 26^c and 27^c are, throughout their peripheral extent, centrally grooved or concaved as at 26^e and 27^e, respectively.

With such a conformation, and bearing in mind the actions that take place under the heat and pressure effect as was above described in connection with Figures 11 and 12, I achieve throughout the regions of the portions 28^a, 29^a, that are, due to the shaping of the faces 26^c and 27^c subjected to the maximum compression, a bonding or flowing together of the materials as was described above in connection with Figure 12, but in the central region of the portions 28^a, 29^a, that is, the regions thereof that are between the grooved or concave portions 26^e and 27^e of the presser and heater elements, a bond that is relatively weak, and in a sense, varying probably with the degree of compression, or practically no bond at all where the concavities or grooves 26^e and 27^e are deep enough or otherwise shaped to transmit insufficient heat or pressure, or both, to effect adhesion, bonding or flowing together.

Thus the junction between two adjacent conductors 36, whether made up in units of two as in Figure 15, or made up in greater multiples, as in Figures 9, 12 and 16, may in cross-section appear substantially as in the somewhat exaggerated view of Figure 18, where throughout the general regions or zones A and B the portions 28^a and 29^a are securely joined together by actions like those described above in connection with Figure 12, being brought about by the pressure and temperature effects produced by the coating or juxtaposed marginal portions of the heater and presser elements 26^b and 27^b of Figure 17, while the central or intermediate zone indicated at C in Figure 18, of the portions 28^a and 29^a are but weakly joined or, as indicated in Figure 18, in somewhat exaggerated form, are not joined together at all. In either case, the cutting is greatly facilitated, whether that be done in the field as by a knife or scissors, or whether that be done in subsequent steps of my process, as by the heater and parting elements 92 of Figures 1, 6 and 7. This central zone C, extending longitudinally and centrally between the two parallel conductors, also acts, because it presents less resistance, as a guide, or to centralize the path along which the cutting or parting device or devices operate, and thus better uniformity of separation is achieved and risk of having the device run into a conductor casing is lessened.

It may be desired, instead of curving portions 28^b and 29^b of the sheet material about the respective sides of the conductors, to have the sheet or web element of one of them, such as the sheet material 28 flat, or substantially flat,

and to loop the companion sheet or web material, such as the upper one 29 about the parallel spaced conductors. In such case, I may retain the configuration of the upper heater and presser elements, as by retaining the drum 27, as shown in Figures 1, 6, 7, 9 and 16, and as for the companion drum 26, I may reduce the height or radial dimension of its heater and presser elements 26^b to any desired extent as, for example, as shown in Figure 19 where they have a height just about sufficient to localize the pressure and heating to the regions 28^a, 29^a between corresponding or juxtaposed heater and presser elements 26^b, 27^b, giving the latter operative faces shaped as described in connection with Figure 11, or as in Figure 17, or any other suitable configuration. In such case, the structure and junctions effected appear substantially as shown in Figure 20, it being understood that pre-shaping of the lower web 28 is not resorted to and where the arrangement of Figure 1 is employed, the fluting device 34 may thus be omitted.

If, in making the structure of Figure 20, it is desired to effect a junction between the casings of adjacent conductors like the junction shown in Figure 18, it will now be clear that, as shown in Figure 21, appropriate shaping of one or both of the companion heater and presser elements according to the shaping shown in Figure 17 may be provided and for purposes of illustration I have in Figure 21 shown the elements 27^b shaped as was described in connection with Figure 17 and in Figure 21 is also indicated the general type of junction described above in connection with Figure 18. Where only one of the companion heater and presser elements is shaped to effect, in coaction with the other one, a lesser or no amount of compression as along the central zone C of Figure 18 or Figure 21, it is preferable to increase the depth of the concavity as at 27^e in Figure 21.

As with other forms, such as those earlier above described, the form of multiple insulated conductor construction of Figures 20 and 21 may be further processed, if desired, as by effecting parting of encased conductors singly or in multiples as described above in connection with Figures 1, 6 and 7. The structure of Figures 20 and 21 may, however, be further processed to produce a structure like that shown in Figure 22.

For purposes of illustration, the structure of Figure 22 is shown as a two-conductor structure though it will be understood that the essentials or advantages may be realized where greater multiples than a single pair of conductors is desired.

In making up the structure of Figure 22, I carry on my process as described in connection with Figures 20 and 21 and, preferably by utilizing the heated parting elements 93 of Figures 1, 6 and 7, I first produce a two-conductor structure as it appears in Figure 20 or Figure 21, disregarding for the moment that those figures are fragmentary or partial views of the structure in greater multiples than two, and then I fold the two-conductor structure longitudinally about substantially the central plane of the joined-together portions 28^a—29^a as an axis, thus bringing the substantially flat casing portions 28^b—28^b of the two casings substantially flatwise against each other and then join together the overlapping end or edge portions 28^k—28^k by a junction indicated in Figure 22 at 28^m.

This junction 28^m is preferably formed by a suitable heated implement or tool which raises

the temperature of the end or edge portions 28^k-28^k to cause the material thereof to bond or merge or flow together, by an action similar to the action above described in connection with the heated parting elements 93.

The resultant structure as shown in Figure 22 may then serve as a two-conductor insulated structure, such as a so-called lamp cord, and in the absence of a junction throughout the adjacent faces of the portions 28^b-28^b , also as indicated in Figure 22 by the transversely extending cap or space Y, parting of the structure, as at the ends thereof where the respective conductors are to be bared for making electrical connections, may be readily effected without impairment of the individual insulating casings of the conductors.

The internal space or cleavage Y extends throughout the length of the structure and serves as a guide for a knife, scissors or other tool that it may be desired to employ to effect separation of the two insulated conductors, the cutting being effected along the plane of the cleavage Y and, of course, through the junction 28^m and through the folded-over joined-together portions 28^a-29^a .

The junction 28^m may be effected in a continuously carried on step as is diagrammatically indicated in Figures 23 and 24 in which any suitable means such as take-off reels and capstan reels (not shown) may be utilized to effect substantially continuous movement of the multiple structure already folded over longitudinally in any suitable way, thus to present the laid together longitudinally end or edge portions 28^k-28^k , as they continue to move, to a heated implement 103, maintained at the desired temperature in any suitable way as by an electric heating unit 104. Any suitable means may be employed to hold and guide the folded-over structure relative to the heated junction-forming implement 103, such as rollers 105 suitably distributed on the two sides of the moving structure, as indicated in Figure 23, and preferably with one of them in juxtaposition to the heated element 103, thus dependably to back up the moving structure during action of the heated element 103 upon the portions 28^k-28^k .

Conveniently, the rollers may be shaped as indicated in Figure 24 to have a configuration fitting the configuration of the folded-over structure and preferably with end flanges of sufficient radius to overlie the upper and lower portions of the folded-together structure as shown in Figure 24 and thus to hold its two portions against un-folding and to maintain the edge portions 28^k-28^k in close engagement so that their material, when heated, for example, to or in the neighborhood of its melting point, will flow together to achieve the junction desired.

The roller 105 to the left of the element 103 in Figure 23 may serve as a smoothing or ironing out roller, like the devices 97 of Figure 10, and preferably also the completed junction is chilled or cooled as by passing it through a cooling bath indicated at 102.

Each longitudinal edge portion 28^k-28^k comprises longitudinally severed but joined-together portions 28^a-29^a so that, irrespective of the particular character of their junction as previously effected, the heated implement 103, may not only merge or flow together the material of the composite edge portions 28^k-28^k , but also merge or flow together the material of the erstwhile components 28^a-29^a thereof.

It will be understood that, in carrying on my method as above described, all of the conductors 36 that are operated upon simultaneously, or in one bank, need not be of the same size throughout; for example, it may be desired to produce several sizes of insulated conductor construction such as, for example, conductors of gauge numbers 14, 16 and 18, and this may be done in the same run. In such case, the several sizes of conductor are preferably divided in groups, for example, equally, and thus about one-third of the conductors 36 may be of one size, the next or middle group may be of another size, and the remaining third, or outside group, of another size. Or, for special or other desired purposes, other groupings of different sizes may be effected.

According to whatever grouping is selected, the heater and presser elements, of whatever form they take and certain of which are illustratively set forth above, are given corresponding spacings, according to the different diameters of conductor and the thickness of the encasing material and, where desired, they may be given effective or operative contact faces of different widths according to the transverse spacings desired, axis to axis, of the parallel encased conductors. Where pre-shaping or preliminary fluting, as with a device like that of Figures 3, 4 and 5, corresponding spacings in the fluting devices 30 are provided and they may be otherwise conformed to the required circumstances as desired.

Where greater flexibility of control or of range or capacity to handle different size spacing or like requirements are desired, I may construct the 35 heater and presser elements as shown in greater detail in Figures 9 and 9^a in which the annular elements 26^b and 27^b are preferably not integral with their respective supporting drums 26 and 27, and are constructed to be sleeved or slipped onto 40 their drums in groups or sequences to provide the various dimensional and space requirements or conditions desired. Preferably, these annular elements 26^b and 27^b have associated with them an annular part such as the parts 26^f and 27^f, respectively, for achieving the desired spacing axially from one another, and in the illustrative and preferred construction the element 26^b and element 26^f are integral as are also the parts 27^b and 27^f.

45 The parts 26^f and 27^f may thus serve as sleeve-like or hub-like supports for the annular heater and presser elements 26 and 27, respectively, for snug reception onto the cylindrical surfaces of the drums 26 and 27, respectively, thus also to 50 insure dependable heat transmission. Any suitable means may be provided to hold them assembled to their respective drums and also to hold them against rotation relative thereto. Thus, as is indicated in Figure 2, the left-hand-ends of 55 drums 26, 27, may be provided with an annular flange or abutment 26^h and 27^h, respectively, against which the left-most elements sleeved onto the drums respectively rest, while the right hand end of these drums may be provided with any suitable clamping means such as the clamping rings 106 and 107 threaded onto suitably threaded 60 end portions of the drums and operated as by a spanner wrench. Preferably also, the drums carry keys 108 and 109, respectively, to take into 65 suitable keyways in the annular sleeve or hub parts, thus to effect a spline and hold the sleeved elements against rotation relative to their drum supports.

70 The units 26^f and 26^b and 27^f and 27^b may be constructed of various axial dimensions and as

sembled to their respective drums in groupings or sequences according to the requirements to be met. Thus, for example, in Figure 9 it has been assumed that the conductors 36 are all of the same size and that the transverse dimension or width of the portions 28^a—29^a that are being joined together are to be the same throughout. Figure 9, therefore, represents an assemblage of units 26^a—26^b and 27^a—27^b which have identical axial dimensions, thus giving the structure heater and presser elements 26^b and 27^b that are all of the same axial dimension, with the axial spacings therebetween, to provide the spaces 26^c and 27^c, all the same.

But in Figure 9^a there is represented an illustrative grouping of units of different axial dimensions to meet a different requirement or condition, and let it be assumed that it is again desired to have the transverse dimensions of the joined-together portions 28^a—29^a all the same throughout, the units assembled to the two drum supports have heater and presser elements 26^b and 27^b of the same axial dimension, but have hub or spacer portions 26^c and 27^c of different axial dimensions according to the different sizes of conductor to be operated upon, thus to vary the axial dimensions of the spaces 26^c and 27^c accordingly. Illustratively, the conductors 36 of the left-hand group of three are of one size and the axial dimensions of the hub and spacer parts 26^c and 27^c are correspondingly dimensioned; the conductors 36 of the middle group of three are of a smaller size and the hub portions of the corresponding units are accordingly of lesser dimension, while the conductors 36 of the right-hand group of three are of largest size and hence the hub and spacer portions are of correspondingly greater axial dimension. By providing units or elements in which the axial dimension of the heater and presser elements 26^b and 27^b are different, as may be desired according to circumstances, I am enabled to make up an assemblage to meet also any needs for different transverse dimensions or widths for the joined-together portions 28^a—29^a, as well as for different sizes of conductors. For any given run of the method and apparatus, any particular requirement may thus be dependably met by making up on the drums of Figures 1, 6, 7, 16 and 19 such a combination of individual units as will meet the particular requirement, it being understood, of course, that the apparatus is constructed in any suitable way for the ready detachability of the drums therefrom, or otherwise, to facilitate replacement, change or rearrangement of the units carried by them.

Depending upon various circumstances or factors, illustrative ones of which are later mentioned herein, I may carry on my method to advantage, by physically segregating the performance of the two steps corresponding to the two stages or steps shown in Figures 11 and 12, and this mode of carrying on my invention will become clearer upon consideration of a preferred form of apparatus therefor, as shown in Figure 25. In Figure 25, the apparatus is physically substantially the same as that described above in connection with Figures 1, 6 and 7, but I have provided two sets of coacting elements to effect the heating and pressing actions, and arrange them so that the first set, in whatever form they take, effects heating of the portions 28^a and 29^a preferably accompanied by some pressing of them together while the second set is arranged immediately thereafter to apply the final or junction-completing pressure to the already

heated companion portions 28^a and 29^a; in effecting such practice of my invention, certain advantages and improved actions are achievable.

For purposes of illustration, let it be assumed that the duplicated coacting elements are in the form of two sets of lower and upper drums 26—27 with annular operative elements 26^b and 27^b, respectively, constructed as above described in connection with Figures 1—20 and in Figure 25 these duplicated units are both represented by the same reference characters 26—27, being preferably structurally identical with each other and with the units 26—27 earlier above described, but in Figure 25 I have distinguished them by designating them, in order from right to left, as unit A and unit B.

To unit A, the conductors 36 and the strip or web elements 28—29 are fed as was above described and as indicated in Figure 25, utilizing the pre-shaping devices 34—35 preceded by pre-heating of the webs if desired, while, as in the case of Figure 1, the pre-fluting may be dispensed with by simply swinging or setting the fluting elements 40—41 apart from each other to bring and hold them out of operative relation to the strip material. Pre-heating, if undesired, may be dispensed with by inserting removable heat baffles or barriers 112 and 113, thus to cut off the flow of heat from the drums 26—27 of unit A to the web elements 28 and 29, respectively.

Through drums 26—27 of unit A is circulated or passed a suitable heating medium as described above in connection with Figure 2, but the setting of or spacing between the faces 28^c, 27^c, of the elements 26^b and 27^b, respectively, whether they are shaped as shown in Figure 11 or as shown in Figure 17 or as may otherwise be desired, is such that, at their points or places of nearest approach is on the order of that shown in Figure 11, being preferably slightly less than the sum of the thicknesses of the strip elements 28 and 29 so that the heated portions 28^a and 29^a as seen in Figure 11 are pressed together to some extent and preferably to an extent just about sufficient to cause these two portions to have some adhesion, one to the other or, where the heating is of a magnitude, as in the preferred case, to give the material of the portions 28^a—29^a some mobility, the pressing of the two portions toward each other is relatively slight and just about enough to merge the mobile materials together at their planes or surfaces of contact, whence the three-fold entity of conductors 36 and strip elements 28—29 emerge from unit A in that condition.

While the elements 26^b and 27^b of unit A are operating upon their respective sheet elements 28 and 29, they thus effect transfer to the portions 28^a—29^a of the desired amount of heat to bring the materials of these portions to the desired condition as earlier described, it being noted that the extent of arcuate contact, for heat transfer, may be varied according to the angles at which the strip elements 28 and 29 enter the throat with respect to the plane of the conductors 36.

Immediately upon emergence from unit A and at the left thereof as seen in Figure 25, the above-mentioned three-fold entity enters the throat formed by the elements of unit B, and the parts 26 and 27 of unit B are set so that the operative faces of the annular elements 26^b and

27^b thereof, whether their peripheral faces are shaped as shown in Figure 11 or are shaped as in Figure 17 or as may otherwise be desired, are, at their points or places of nearest approach, spaced apart by that amount corresponding to the amount of compression that it is desired to subject the companion portions 28^a—29^a. Illustratively, the spacing here may be on the order of one-half of the sum of the thicknesses of the two strip elements 28—29, and hence would be as shown in Figure 12. At this stage the actions generally described above in connection with Figure 12 take place, such as the flowing together of the plastic material of the portions 28^a—29^a or the displacement or migration thereof when mobile under the heat effects brought about by unit A, and the junctions above described thus completed or concluded.

But preferably, instead of circulating a heating medium through the drums 26—27 of unit B so as to continue the flow or supply of heat to the portions 28^a—29^a undergoing union, I hold the elements 26^b—27^b of unit B at a lower temperature, utilizing the same structural and circulating means or system as described above in connection with Figure 2. In thus causing the presser elements 26^b—27^b of unit B to be operative at a lower temperature than are the heater and presser elements of unit A, tendencies of the material of the heated portions 28^a—29^a to adhere to the operative faces of the presser elements are counteracted. Thus, for example, the presser elements 26^b—27^b of unit B, functioning to effect compression on the order of that illustratively described above in connection with Figure 12, are at a lower temperature than the portions 28^a—29^a which they respectively engage and they withdraw heat from the surface portions of the latter to a sufficient extent to chill the skin thereof and thus in effect prevent adhesion of the materials thereto; but the withdrawal of heat is not sufficiently rapid to destroy plasticity, or tackiness or mobility of the material of the portions 28^a—29^a at and underlying their initial surfaces of engagement, and hence the junction of the portions 28^a—29^a is not detrimentally affected. Where the presser elements are annular or rotary, as in unit B, and are aligned with respect to unit A as shown in Figure 25, any arcuate contact between them and their respective portions 28^a—29^a is a minimum for any given setting.

A suitable medium for passage through the parts 26—27 of unit B is a suitable liquid, such as water or brine, supplied to the intake passages 83 of the drums of unit B from any suitable source or means and supplied at the desired temperature below the temperature to which the material of the portions 28^a—29^a is heated in unit A. Thus cold water or brine may be utilized. Preferably also, suitable heat baffles or shells 114 and 115, made of a suitable heat-insulating material like the baths 112—113, are provided to heat-insulate unit A from unit B.

Thus, not only may sticking or adhering of the hot or plastic or semi-fluid material of the portions 28^a—29^a to the compression-effecting elements be counteracted, but also and thereby higher speeds of movement of the material and conductors through the apparatus may be achieved and hence rate of production increased. Also the withdrawal of heat progressively, first from the outer or surface regions of the portions 28^a—29^a and then more and more from the internal and now already compressed and joined-

10 together portion 28^a—29^a in effect "freezes" the junction in the stage of operation effected by unit B, thus lessening chance of even partial separation of the otherwise still pliantly warm merged-together sealed areas as might be caused after emergence from unit "B" either by the natural gravity pull or other strains of the conductors or by possible tendency of the strip material to return to its original flat, sheet form. Thereafter, I prefer nevertheless to subject the structure to the action of cooling bath 81 and thereafter the construction may be further processed, according to the particular form of final structure desired as has been above described in detail.

15 The two-unit arrangement and the corresponding segregation physically of the two steps operate toward the achievement of other advantages as well. Thus, for example, heat-applying unit A may, if desired, be operated at higher heat or temperature levels to bring about a more rapid transfer of heat to the material of the two strip or casing elements or to bring the material to a higher state of fluidity or mobility, since it is possible to avoid the application in unit A of material or substantial pressures and thus, adhesion or sticking of the heated material to the heater elements is far less likely to take place.

20 30 Also, with the higher state of plasticity and mobility of the material, the junction, as by flowing or merging the practically molten material of the two portions 28^a—29^a together may be more quickly and dependably achieved, and 35 also at the desired compression or pressure application, the relatively cold presser elements of unit B chilling or freezing the external or surface portions which they directly engage and thus, though they operate under pressure, adhesion or sticking to the elements of unit B is counteracted.

40 45 Also, in such an arrangement I preferably utilize supporting drums and hence also heater and presser elements that are of lesser diameter than is preferably the case where the physical relationships of Figures 1, 6 and 7 are employed, and thereby the cost per drum unit reduced. Also, in utilizing smaller diameters, units A and B may be spaced more closely together so that 50 the presser elements of unit B may operate in quicker sequence to the step carried on in unit A and thereby lessen the possible effect of heat loss from the heated portions in their transition from the place of heat application in unit A to 55 the point or stage of substantial pressure application in unit B.

60 In the larger views of the drawings, and as earlier above referred to, I have indicated at x an internal space or clearance between the conductor and its individual casing and for convenience of illustration this clearance has been shown in the drawings as concentric with the conductor and the casing has been shown also internally and externally concentric with the conductor; 65 it will be understood, however, that such geometric concentricity is not necessarily inherent in the structure and is used in the drawings to indicate a preferred looseness or play between the conductor and its casing. In actual practice, 70 the pliancy of the casing material gives the clearance or space x a varied or variable cross-sectional shape in that usually the portions 28^b—29^b engage the encased conductor principally at the upper and lower portions or apexes as 75 viewed in the large scale drawings, each casing

somewhat elongating itself transversely along a horizontal axis through the center of the conductor as the figures of the drawings are viewed. In the preferred form, therefore, and hence where the desired looseness is present, each conductor casing, particularly in the multiple conductor structure, appears in cross-section to have a horizontal dimension greater than the vertical dimension and hence may be said to have a major axis, which is horizontal as the drawings are viewed, and a minor axis which is vertical.

As above indicated, certain materials or formulations that may be employed have a tendency to shrink, particularly when subjected to heat, and the looseness I am enabled to achieve in practicing my process permits the material of the casing to accommodate itself to varying conditions, whether in course of fabrication or in actual practical application or use, without becoming subjected to detrimental stresses.

Thus there is sufficient leeway, due to the looseness or clearance x or due to the corresponding greater internal periphery of the casing as compared to the external conductor periphery, so that shrinkage of the casing material where it happens to have a shrinking characteristic does not proceed to a point where it becomes detrimentally tensioned about the conductor itself.

The extent of clearance or looseness x may vary according to desire, but is preferably commensurate with the particular diameter or diameters of conductor or conductors to be encased. Thus, for example, where all of the conductors are of the same size and uniform heater and presser elements and spacings are utilized, as in Figure 9, for example, a substantial uniformity of clearance space x results. Where different sizes of conductors are encased, as in Figure 9a, the commensurate dimensioning of heater and presser elements and spaces makes it possible to vary or proportion the actual clearance x to the respective sizes of conductors being encased. On the other hand, I have found that even with equal spacings and dimensions for the heater and presser elements, as, for example, in Figure 9, the conductors may be of differing sizes with the result that the clearance x about the smaller sized conductors gives a somewhat greater looseness than the clearance x about larger sized conductors; it is preferred, however, to proceed according to an arrangement like that described in connection with Figure 9 since in that manner more efficient use is made of the transverse width of the web or strip elements 28 and 29 in that a lesser fraction of their widths is thereby utilized in providing a satisfactory amount of looseness.

A junction effected in the manner above described in connection with Figures 17 and 18 has a number of advantages, some of which are mentioned above, in that separation or parting, as by a tool, is facilitated, whether such parting is effected as part of the processing or is later on effected in the field. However, and particularly where the two-unit arrangement of Figure 25 is employed, I may, preferably by way of the cold unit B perform steps upon the multiple insulated conductor structure to effect or facilitate parting and for this purpose I may proceed according to Figures 26-28. Thus all or as many as may be desired, of the companion elements 26b-27b, according to the ultimate result desired and according to the grouping or assembly of the annular units on their respective drums as described above in connection with Figures 9 and 9a, have companion or coacting

parts to effect mechanically a severance, cutting or punching or weakening of the joined-together portions 28a-29a, preferably along a central zone, line or plane, leaving zones of complete securing together to either side thereof, and causing them to function as the multiple conductor entity continues to move toward the left as viewed in Figures 1, 6, 7 and 25.

Thus, for example, the elements 26b may be provided with a central peripherally extending groove or slot 26p, as shown in Figures 26 and 27, and I provide the element 27b with means to coact with the slot 26p to effect a shearing, punching or cutting action upon the compressed junction 28a-29a, and where complete severance or parting is not desired, this means may comprise a series of peripherally projecting spaced elements 27p, somewhat stud-like in form and mounted on the member 27b in any suitable manner, as by a force fit into suitable holes or slots in the element 27b, as indicated in Figures 26 and 27.

The projecting portions of the elements 27p may be of any desired cross-section or shape, 25 illustratively rectangular in cross-section, with their smaller dimensions extending axially while the slot 26p has a width to relatively snugly receive, as with a sliding fit, the smaller dimensions of the parts 27p, as the two drums rotate. 30 In shape, when viewed as in Figure 27, the projecting portions may have sloping sides. The depth of the slot 26p and the length of the projecting portions of the parts 27p are such as to 35 allow for an adequate range of adjustment of the drums toward or away from each other without effecting such separation that the parts 27p do not, at least to some extent, enter the slot 26p.

In the arrangement of Figure 25, therefore, and with the desired assembly in unit B of presser elements 26b-27b constructed as just described, the companion peripheral faces of elements 26b-27b operate upon the material of the portions 28a-29a as above described, and as those steps are being carried on and with the continued rotation of the drums, the parts 27p sever or punch, and in coaction with the walls of the slot 26p effect a shearing, of the joined-together portions 28a-29a, each throughout its range of operation, and where spaced so as not to effect complete severance, each part 27p effects a severance throughout its own range, as indicated in Figure 28 at E.

This action need not be in the nature of a punching action in the sense that each part 27p physically punches or stamps out a portion of the material. Since the material, even though it is being cooled off by the cold presser elements of unit B has sufficient softness and since the width of the parts 27p of the slot 26p is after all very small, a parting or severance is effected. With the relatively rapid heat withdrawal by the elements of unit B, and the major heat withdrawing action that takes place at the point or place of maximum compression between elements 26b-27p, at which point or place a part 27p is completely projected through the junction and has its outer end extended into the slot 26p, flow of material at the internal and warmest portions of the junction as might otherwise effect a reunion of the severed or parted material, does not take place, and hence the multiple conductor structure emerges, where complete severance is not effected between adjacent conductors, in a form substantially as shown in Figure 28, the joined-together portions 28a-29a

have extending centrally and lengthwise thereof a zone comprising spaced regions E of parting or severance, leaving zones of unimpaired junctions to either side thereof, and it is through the central zone and along the line of these regions E that subsequent parting as by a tool, such as scissors, is facilitated in the field or by a heated parting element such as the element 93 of Figures 1 and 25 if such parting, followed by the smoothing or ironing operation of the device 97 is desired in the further processing of the conductor. Where the parts 27p do not effect complete severance between adjacent conductors, the space regions E of parting or severance also facilitate tearing, along the line of the regions E, of one encased conductor structure from an adjacent one.

If parting or separation is effected in the field, the junctions on both sides of the line or plane of separation, both with the structure of Figures 26-28 and with structures having junctions like that shown in and described in connection with Figure 18, are secure and sealed throughout, thus insuring the integrity of the conductor casing. It will, of course, be understood that, if desired, the elements 26b-27b, even when shaped as at 26s and 27s in Figure 18 and others, may be provided with the slot 28p and the severing means 27p, as in Figures 26 and 27, thereby effecting a line of regions E in the two separated or weakly-joined central parts of the portions 28a-29s.

Even though complete parting or severance in the regions E of Figure 28 is not effected, as may be the case if the elements 26b-27b of Figures 1, 6 and 7 include structures like that of Figures 26 and 27, in which case it is possible that some reunion in each region E takes place before sufficient cooling can be effected, such regions would nevertheless act appropriately to facilitate subsequent severance or parting where that is desired.

Thus it will be seen that there has been provided in this invention a conductor construction and a method and apparatus for making the same in which the various objects above noted are successfully achieved. The insulated conductor construction itself is of a thoroughly practical character, lends itself to wide flexibility of application or adaptation, is capable of being installed where it is subjected to numerous bends and may otherwise be repeatedly flexed without compounding stresses as will detrimentally affect the conductor or its casing. The casing is tough, strong, flame-proof, resistant to the effects of sunlight, resistant to oxidation, resists mutilation as by blows or forces tending to abrade it, particularly where the insulated conductor is utilized without superimposing upon the encasing sheet material any other covering, casing or the like, and the construction lends itself to embodiment in various colors or pigmentations, according to the particular formulation of material employed, since certain of them, such as "Koroseal," can be readily pigmented and utilized in corresponding colors, and even also utilized in their transparent or translucent form. Moreover, comparative smallness or diminutiveness of cross-section, compared to other or known insulated conductor structures, is possible, and yet the resultant insulated conductor structure is superior in many respects over other constructions; also, if used as a base or core for building up various types of cables, such as armored ca-

ble, non-metallic sheathed cable, and the like, substantial savings in the materials of the superimposed cover or coverings may be effected because of the comparatively small over-all cross-section above mentioned.

Where the material employed is transparent or translucent and the structure is made up in multiple-conductor form, conductor identification or coding may be effected by using, instead of bare conductors 36, conductors that have been previously covered with any suitable coloring or colored material, according to the color code desired; also, identification may, of course, also be effected where the sheet material employed is opaque and, in such case, identification is had at the ends of the multiple conductor structure. For other reasons than conductor identification, it might be desired to apply the sheet material to a conductor or conductors already provided, in any known manner, with an insulating covering, in one or more layers or the like. For such reasons as these, it will therefore be understood that, in the following claims, the term "conductor" or "conductors," unless otherwise limited, comprehends not only a bare conductor or conductors but also a conductor or conductors having thereon a covering or coating.

The junctions effected to either side of each conductor are, moreover, strong, durable and dependable, can be achieved according to my method without incurring the disadvantages inherent in methods depending upon vulcanization, where the time element is an undesirable factor, and tests have shown the soundness and strength of the junctions I am enabled to achieve.

Conductor construction, when made up according to my invention, has moreover a greatly increased range of application and uses; for example, the resistance of the materials to oils, greases and other petroleum products materially enlarges the field of use. Also, the junctions effected in the strip material have a wide range of operating temperatures, corresponding to that of the particular formulation of material that may be employed. Accordingly, the insulated conductor construction may be used in installations subjected to high heat effects, or in installations subjected to opposite extremes, or in installations subjected, or likely to be subjected, to both extremes. An illustrative range may be from an upper temperature limit on the order of 180° F. to a lower temperature limit on the order of 25° to 40° below 0° F.

Moreover, it will be seen that the method and apparatus lend themselves to wide flexibility of operation according to production needs such as requirements for single or multiple insulated conductor constructions, and also requirements such as different sizes of conductors employed. Also, it will be seen that linear footage of conductor may be produced at a high rate.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. In a method of insulating electrical conductors, the steps which comprise moving a plurality of spaced parallel conductors axially with their axes lying in substantially the same plane,

effecting movement of two pre-fabricated sheet elements, made of a flexible non-vulcanizable insulating material having thermoplastic characteristics such that, when heated substantially above the normal temperature of the sheets, the material is given a plastic state appropriate for flowing together under pressure, into juxtaposition to each other and each to one side of said plane and in the same direction and at substantially the same speed as said moving conductors, thereby to bring said spaced conductors in between said two sheet elements, heating said two sheet elements during movement but only in transversely spaced regions thereof corresponding to those juxtaposed portions of the sheet elements that intervene said spaced conductors to bring said portions to a substantially plastic state and thereby leave intermediate portions that are to engage and envelop respective conductors in substantially non-plastic state, and pressing juxtaposed plastic intervening portions of said two sheet elements into engagement with each other as said sheet elements and conductors continue to move, thereby to bond said juxtaposed intervening portions together.

2. The method as claimed in claim 1, in which the step of pressing engaged intervening portions together comprises pressing them during movement, to a dimension materially less than the sum of their initial thicknesses to flow the plastic material thereof laterally to relieve possible tensioning about the conductors of said intermediate portions of said sheet elements.

3. In a method of insulating electrical conductors, the steps which comprise moving together as a unit two strip elements, made of a flexible non-vulcanizable insulating material having thermoplastic characteristics such that, when heated substantially above the normal temperature of the strip elements, the material is given a plastic state, with a conductor therebetween and during movement bringing respective longitudinal side portions of said strip elements into juxtaposition to each other, heating only said longitudinal side portions to a temperature to cause the material thereof to be substantially plastic and thereby to leave those portions of said strip elements that are respectively juxtaposed to the conductor in substantially non-plastic state, and during movement pressing the heated substantially plastic juxtaposed side portions together to effect a bond therebetween.

4. In a method of insulating electrical conductors, the steps which comprise laying about the conductor flexible non-vulcanizable insulating sheet material having thermo-plastic characteristics such that, when heated above the normal temperature thereof the material acquires plasticity, and bringing portions thereof into engagement with each other lengthwise of the conductor to substantially complete the envelopment of the conductor by said sheet material, heating the material of only said engaged portions to a temperature to effect plasticity of said portions suitable to join them together and thereby leave the remaining portions of said sheet material that envelop the conductor in substantially non-plastic state, and pressing the said heated juxtaposed portions together to effect bonding therebetween.

5. In a method of insulating electrical conductors, the steps which comprise moving a plurality of conductors axially with the conductors in spaced parallel relation and with their axes lying in substantially the same plane, effecting movement of two sheet elements, made of a flex-

ible non-vulcanizable insulating material having thermo-plastic characteristics, into juxtaposition to each other and each to one side of said plane and in the same direction and at substantially

5 the same speed as said moving conductors, thereby to bring said spaced conductors in between said two sheet elements, heating said two sheet elements during movement but only in transversely spaced regions thereof corresponding to those juxtaposed portions of the sheet elements that intervene said spaced conductors and confining the heating thereof at each of said aforesaid regions in at least two transversely spaced zones to bring the zones of said juxtaposed portions to a substantially plastic state, thereby leaving intermediate portions of said two sheet elements that are to engage and envelop respective conductors in substantially non-plastic state, and pressing juxtaposed plastic zones of said intervening portions of said two sheet elements into engagement with each other as said sheet elements and conductors continue to move, thereby to bond said two sheet elements together at each of said transversely spaced regions in two transversely spaced zones.

6. The method as claimed in claim 5, comprising also the step of parting two adjacent insulated conductors by longitudinally severing the intervening portions along the zone intervening said 30 two transversely spaced zones.

7. An insulated multiple conductor construction comprising a plurality of spaced parallel conductors interposed between two pre-fabricated sheet elements made of a flexible non-vulcanizable insulating material having thermo-plastic characteristics such that it becomes plastic at temperatures beyond the operating range of temperatures of said sheet elements, the portions of said elements that lie against said conductors 35 being free from bonded engagement therewith and the portions of said sheet elements bridging the spaces between adjacent conductors being brought together and joined together by a junction formed by heating the material of said portions to a substantially plastic state and in such state pressing it together to bond the material of the two portions to each other.

8. An insulated multiple conductor construction comprising a plurality of spaced parallel conductors interposed between two pre-fabricated sheet elements made of a flexible non-vulcanizable insulating material having thermo-plastic characteristics such that it becomes mobile at temperatures beyond the operating range of said 50 sheet elements, the portions of said elements that lie against said conductors being free from bonded engagement therewith and the portions of said sheet elements bridging the spaces between adjacent conductors being joined together by a junction which is the result of flowing the material of said portions together under conditions of heating to temperatures at which the thermo-plastic characteristics of the material give it mobility to flow the material of said portions 55 together.

9. An insulated multiple conductor construction comprising a plurality of spaced parallel conductors each enveloped by and between portions of two pre-fabricated sheet elements made of a flexible non-vulcanizable insulating material having thermo-plastic characteristics, said portions being free from bonded engagement with said conductors and the portions of said sheet elements between adjacent conductors being united as a 70 result of heating the material thereof to a tem-

perature to cause adhesion and pressing the heated portions together to form longitudinally connected continuous jackets, one for each conductor, the portions of the sheet elements that form the jackets for the conductors having a greater internal peripheral dimension than that of the conductors, thereby loosely jacketing their respective conductors.

10. An insulated multiple conductor construction comprising a plurality of spaced parallel conductors each loosely enveloped by and between portions of two pre-fabricated sheet elements made of a flexible non-vulcanizable insulating material having thermo-plastic characteristics, with the longitudinally extending marginal areas of the portions of said sheet elements brought together and bonded thermo-plastically to form longitudinally connected continuous jackets, one for each conductor, with means forming a longitudinally extending parting zone between jackets along which one may be separated from its adjacent one.

11. An insulated conductor construction comprising a conductor having thereabout and free from bonded engagement therewith flexible non-vulcanizable pre-fabricated insulating sheet material having thermo-plastic characteristics such that, when heated substantially above the operating temperature range of the insulated conductor construction, the material is given a plastic state, said insulating sheet material having portions extending lengthwise of the conductor joined together by a junction formed by heating the material of said portions to a substantially plastic state and pressing them together while plastic.

12. An insulated conductor construction comprising a conductor having thereabout and free from bonded engagement therewith flexible non-vulcanizable pre-fabricated insulating sheet material having thermo-plastic characteristics whereby it has a melting point materially above the operating temperature range of the insulating sheet material in the conductor construction, said sheet material having portions extending lengthwise of the conductor joined together by a junction formed by heating the material of said portions to substantially its melting point and flowing them together.

13. An insulated conductor construction comprising at least two parallel spaced conductors enveloped in a flexible non-vulcanizable pre-fabricated insulating material having thermo-plastic characteristics, with the portions of the two layers of sheet material that lie between the conductors being joined together along two longitudinally extending and spaced zones by junctions formed by heating the material at said zones to bring it to a substantially plastic state and pressing the heated zones of the two layers together while in plastic state.

14. An insulated conductor construction comprising at least two parallel spaced conductors enveloped in a flexible non-vulcanizable pre-fabricated insulating material having thermo-plastic characteristics, with the portions of the two layers of sheet material between the conductors being joined together along two longitudinally extending and spaced zones by junctions formed by heating the material of the two layers to bring it to a substantially plastic state and pressing the two layers together while in its plastic state, there being a zone of separation or parting in the junction to facilitate physical segregation.

15. The method as claimed in claim 1 in which

the step of pressing together the material of the said intervening portions is carried on simultaneously with the step of heating said intervening portions.

16. The method as claimed in claim 1 in which the step of pressing the said intervening portions together is carried on independently of and subsequently to the step of heating the said intervening portions and is accompanied by the withdrawal of heat from the said intervening portions from the external surfaces thereof to thereby set the bonded-together material thereof.

17. An apparatus having means for moving axially a plurality of conductors in spaced parallel relation and with their axes lying in substantially the same plane, with means for moving two sheet elements of pliant insulating material into juxtaposition to each other and each to one side of said plane and in the same direction and at substantially the same speed as said moving conductors, the combination of heater and presser means for heating and pressing together those portions of the two sheet elements that intervene said spaced conductors to bring them into engagement with each other and to lay intermediate portions respectively against the conductors, said heater and presser means comprising companion presser elements having those parts thereof that are juxtaposed respectively to the spaced conductors, spaced apart by a distance greater than the total thickness of the conductor and the two sheet elements, thereby to avoid direct pressing together of the conductors and the respective intermediate portions of said sheet elements laid against them, said heater and presser means comprising heater means having companion transversely spaced heater elements for effecting heating of the material of only said intervening portions of said two sheet elements to bring it to a plasticity to secure them together when pressed together and thereby avoid bringing the material of said intermediate portions to plasticity.

18. An apparatus as claimed in claim 17 in which said companion spaced heater elements comprise respectively said companion presser elements, and means for heating said presser elements.

19. An apparatus as claimed in claim 17 in which said companion presser elements comprise two sets of companion annular members presenting juxtaposed substantially cylindrical operative faces for engagement with said intervening portions of said sheet elements, and driven drums for respectively mounting said two sets of annular members, the latter having spacer means therebetween of lesser diameter than said annular members, said spacer means comprising the aforesaid parts that are juxtaposed respectively to the spaced conductors.

20. An apparatus as claimed in claim 17 in which said companion presser elements comprise respectively two sets of companion annular elements, each set having rotary means for aligning and supporting the annular members thereof, and in which said companion spaced heater elements comprise two sets of axially spaced annular members, each set having rotary means for supporting and aligning the members thereof, and means for heating said last-mentioned annular members to heat said intervening portions of said sheet elements.

21. An apparatus as claimed in claim 17 in which said companion presser elements comprise

two sets of companion annular members presenting juxtaposed substantially cylindrical operative faces for engagement with said intervening portions of said sheet elements, and driven drums for respectively mounting said two sets of annular members, the latter having spacer means therebetween of lesser diameter than said annular members, said spacer means comprising the aforesaid parts that are juxtaposed respectively to the spaced conductors, and means for withdrawing heat from said annular members to thereby set the plastic material of said intervening portions of said sheet elements as they are pressed together by said annular members.

22. An apparatus as claimed in claim 17 in which said heater elements have means for localizing the heat applied to said intervening portions in two transversely spaced zones within the width of each pair of engaged intervening portions.

23. An apparatus as claimed in claim 17, provided with means for cooling the conductors whereby to cool said intermediate portions of said sheet elements.

24. An apparatus as claimed in claim 17 in which heated severing means are positioned in the plane of movement of at least one pair of secured-together intervening portions to raise the temperature of the material of the latter and as thus heated to sever them, and means for smoothing off or ironing down the components of the severed intervening portions of said sheet elements.

25. An apparatus as claimed in claim 17 in which said companion heater elements are spaced from said companion presser elements in the direction of movement of said conductors and sheet elements to thereby cause the operation of said heater elements upon said intervening portions to take place in advance of the operation thereon of said presser elements.

26. An apparatus as claimed in claim 17 in which there is means for cooling the assembled conductors and sheet elements to withdraw heat therefrom and to restore the material of the now secured-together intervening portions to its normal condition.

27. An apparatus having means for moving axially a plurality of conductors in spaced parallel relation and with their axes lying in substantially the same plane, with means for moving two sheet elements of pliant insulating material into juxtaposition to each other and each to one side of said plane and in the same direction and at substantially the same speed as said moving conductors, a plurality of transversely spaced individually restricted heater means for heating said two sheet elements during movement but only in transversely spaced regions thereof corresponding to those juxtaposed portions of the sheet elements that intervene said spaced conductors to bring said portions to a substantially plastic state and thereby leave intermediate portions that are to engage and envelop respective conductors in substantially non-plastic state, and presser means for pressing said plastic intervening portions of said two sheet elements into engagement with each other as said sheet elements and conductors continue to move, thereby to bond said juxtaposed intervening portions together.

28. An apparatus as claimed in claim 27 having also parting means that comprises means coacting with and operating during the action of said presser means to effect parting in a direc-

tion transversely of the junction of said intervening portions.

29. An apparatus as claimed in claim 27 provided with parting means that comprises means coacting with and operating during the action of said presser means to effect parting in a direction transversely of the junction of said intervening portions, and means for withdrawing heat from said presser means to enhance the setting of the material of said intervening portions.

30. An insulated multiple conductor construction as claimed in claim 9 in which the respective portions of said two sheet elements that envelop the conductors are each internally concave and together are of 360° in extent internally, and of greater radius internally than the external radius of the enveloped conductor.

31. An insulated multiple conductor construction as claimed in claim 9 in which, of the two portions of said two sheet elements that envelop each conductor, one is substantially flat and substantially tangent to the conductor, and the other is internally concave and arched about the conductor and has said flat portion as a base.

32. An insulated multiple conductor construction as claimed in claim 10, in which the said means forming the parting zone comprises a line of regions of parting extending lengthwise intermediate of adjacent jackets.

33. An insulated multiple conductor construction as claimed in claim 10 in which the said means forming a parting zone comprises a longitudinally extending intermediate zone between adjacent jackets and in which zone the sheet elements are substantially unsecured and lie in a plane substantially parallel to a plane joining the axes of adjacent conductors.

34. An insulated multiple conductor construction as claimed in claim 10 in which the said means forming a parting zone comprises two layers of insulating sheet material lying substantially flatwise against each other along a plane substantially at right angles to a plane joining the axes of adjacent conductors, with longitudinally extending intermediate portions of said two layers free from bonding one to the other.

35. An insulated multiple conductor construction as claimed in claim 10 in which said means forming the parting zone comprises a longitudinally extending zone between adjacent jackets and in which zone the sheet elements are substantially unsecured and have therein lines of regions of parting.

36. An apparatus as claimed in claim 27 in which said presser means comprising companion rotary elements operating at a lower temperature than that of said intervening portions for pressing the latter together, said companion rotary elements having companion parts operating to sever at least one pair of secured-together intervening portions along a line intermediate of the junction securing them together.

37. An apparatus as claimed in claim 27 in which said presser means comprises two companion sets of transversely spaced rotary elements positioned respectively on the two sides of said plane and having effective widths less than the spacing between conductors for action upon said intervening portions of said sheet elements, certain of said companion rotary elements having respectively recess means and projecting means for entering said recess means during rotary movement of said rotary elements to thereby sever the secured-together intervening portions.

38. An apparatus as claimed in claim 27 provided with means operating in advance of said heating means for raising the temperature of the entire material of at least one of said two sheet elements to improve its pliancy, with means operating upon the resultant more pliant sheet element to flute it and thereby provide therein flutes for one or more of said conductors.

39. The method as claimed in claim 1, comprising also the steps of raising the temperature of at least one of said sheet elements to improve its flexibility and then forming flutes therein corresponding to one or more of said conductors, all in advance of the aforesaid step of heating.

40. An apparatus as claimed in claim 17 in which said companion presser elements comprise two sets of companion annular members presenting juxtaposed substantially cylindrical operative faces for engagement with said intervening portions of said sheet elements, driven drums for respectively mounting said two sets of annular members, the aforesaid parts that are juxtaposed respectively to the spaced conductors comprising hub-like portions, one for each annular member and each hub-like portion of lesser external diameter than the external diameter of said annular members and having an internal diameter to substantially match the diameter of the drum mounting it, whereby the hub portions of the annular members of said two sets are sleeved onto their respective drums, and means, one for each drum and each coacting therewith, for removably clamping together in axial direction the hub portions of the set of annular members carried by the drum.

41. An apparatus as claimed in claim 17 in which said companion presser elements comprise two sets of companion annular members presenting juxtaposed substantially cylindrical operative faces for engagement with said intervening portions of said sheet elements, driven drums for respectively mounting said two sets of annular members, the aforesaid parts that are juxtaposed respectively to the spaced conductors comprising hub-like portions, one for each annular member

and each hub-like portion of lesser external diameter than the external diameter of said annular members and having an internal diameter to substantially match the diameter of the drum mounting it, whereby the hub portions of the annular members of said two sets are sleeved onto their respective drums, the axial dimension of the hub portions of at least two companion annular members of said two sets being different 5 from the axial dimension of the hub portions of other companion annular members to thereby provide, adjacent those companion annular members that have said different axially dimensioned hub portions, a substantially correspondingly different axial spacing from the next adjacent companion annular members and thereby lay intermediate portions of correspondingly different width of said two sheet elements against that conductor moving in said differently dimensioned 10 spacing, and means, one for each drum and each coacting therewith, for removably clamping together in axial direction the hub portions of the set of annular members carried by the drum.

42. An apparatus as claimed in claim 27 in 25 which said heater means are spaced from said presser means in the direction of movement of said conductors and sheet elements to thereby cause the operation of said heater means to take place in advance of the operation thereon of said 30 presser elements, said presser means comprising companion rotary elements operating at a lower temperature than that to which said heater means heats said intervening portions of said two sheet elements for pressing said heated intervening portions together, certain of said companion rotary elements having respectively recess means and projecting means for coacting with said recess means during rotary movement of said rotary elements and operating upon the 35 secured-together intervening portions to change the conformation of the latter along substantially a line intermediate of the junction securing them together, thereby to facilitate separation along said line.

CHARLES W. ABBOTT.
